UNITED STATES PATENT OFFICE.

WILLIAM H. CAVNISS, OF HELENA, ARKANSAS, ASSIGNOR OF ONE-HALF TO
WILLIAM MCCOY, OF SAME PLACE.

CAR-COUPING.

SPECIFICATION forming part of Letters Patent No. 593,195, dated November 9, 1897.

Application filed April 30, 1897. Serial No. 634,610. (No model.)

To all whom it may concern:

Be it known that I, WILLIAM H. CAVNISS, a citizen of the United States, residing at Helena, in the county of Phillips and State 5 of Arkansas, have invented a new and useful Car-Coupling, of which the following is a specification.

This invention relates to improvements in car-couplings.

10 The object of the present invention is to improve the construction of car-couplings and to provide a simple, strong, and durable one capable of coupling automatically and adapted to be readily uncoupled from the 15 tops and sides of cars without going between them.

The invention consists in the construction and novel combination and arrangement of parts, as hereinafter fully described, illustrated in the accompanying drawings, and pointed out in the claims hereto appended.

20 In the drawings, Figure 1 is a perspective view of a car-coupling constructed in accordance with this invention and shown applied 25 to a car. Fig. 2 is a longitudinal sectional view. Fig. 3 is a horizontal sectional view showing two draw-heads coupled. Fig. 4 is a transverse sectional view showing two draw-heads coupled.

30 Like numerals of reference designate corresponding parts in the several figures of the drawings.

1 designates a draw-head mounted on a car 2 between draft-timbers 3 and supported by 35 a carrier-iron 4 in the usual manner, and it is capable of a limited lateral movement, being pressed or held by a spring 5 for a purpose hereinafter described. The spring 5, which engages the outer edge of the draw-head and 40 which forces the same inward, is interposed between one of the draft-timbers and the said draw-head, as clearly illustrated in Fig. 3 of the accompanying drawings.

The draw-head is provided at its outer side 45 with a substantially straight arm 6, and it has a curved arm 7 at the opposite side to form a recess to receive the end of the outer arm 6 of another draw-head. The outer end of the arm 6 is enlarged and rounded, as

shown, and forms a shoulder 8 at the inner 50 side of the arm, and the other arm 7 is curved at its inner face to conform to the configuration of the arm 6, as clearly illustrated in Fig. 3. The inner end of the arm 6 is hollowed out or recessed to complete the recess formed 55 by the arm 7, and a shoulder 10 is provided at the end of the recess to interlock with the outer shoulder 8 of another draw-head. The inner faces of the draw-heads conform to the configuration of each other in order to inter- 60 lock, and the recesses at the inner ends of the draw-heads are sufficiently large to permit the draw-heads sufficient lateral movement to disengage each other when uncoupled.

Each draw-head is provided at the inner 65 face of its arm 6 with a concavity 11, and when two draw-heads are coupled the concavities 11 form a socket to receive a coupling-ball 12, which connects the two draw-heads. The socket formed by the concavities 11 is of 70 the same width as the ball, but is enlarged longitudinally of the draw-head to permit a limited play of the parts.

The ball 12, which is connected to a chain or similar flexible connection 13, is adapted 75 to be drawn upward into a tubular housing or casing 14, mounted on the draw-head over the concavity, the top of which is sufficiently enlarged to permit the ball to drop into the same. The casing 14, which is closed at the 80 top by a suitable head, is provided with an exteriorly-arranged support 15, on which is fulcrumed the lever 17, extending upward and downward from the support 15 and having its lower end connected with a recipro- 85 cating slide 18. The slide 18, which is disposed longitudinally of the draw-head in suitable ways of the arm 6, has its front or outer end arranged to project across the bottom of the casing, as illustrated in Fig. 2 of the ac- 90 companying drawings, to support the ball and prevent the same from dropping into the concavity. The inner end of the slide is provided with a transversely-disposed L-shaped arm 19, arranged when the slide is extended for- 95 ward to be engaged by a draw-head, whereby when two draw-heads come together for coup- ling the slide will be moved inward or rear-

ward to release the ball and cause the same to couple the draw-heads. The L-shaped arm has one portion arranged in a horizontal plane in a recess of the draw-head, and the other portion, which depends from the horizontal part, is received into a pocket or cavity 20, whereby it is prevented from being crushed or otherwise injured during the operation of coupling.

10 The upper end of the lever 17 is provided with a substantially L-shaped arm 21, which extends into the casing 14 and depends from the upper portion of the same. When the slide is extended forward, the L-shaped arm 21 is drawn outward with its depending portion substantially vertical, as illustrated in full lines in Fig. 2 of the drawings, and when the slide is moved rearward the L-shaped arm 21 is thrown into the casing 14 in the position 15 illustrated in dotted lines in Fig. 2 of the drawings, so that the depending portion is disposed at an inclination, whereby when the ball is drawn upward for uncoupling it will engage the inclined portion of the L-shaped arm and automatically move the slide forward 20 and set the parts for automatic coupling.

25 The chain 13, which passes through a perforation of the top of the casing 14, extends to the top of the car to enable the operation 30 of uncoupling to be performed from that point, and oppositely-disposed chains 22 are provided for enabling the operation of uncoupling to be performed from either side of the car. The chains 22, which are secured at 35 their outer terminals to the car, extend upward and inward at an inclination and pass over a pulley 23, and are secured at their inner terminals to the chain 13 a sufficient distance below the pulley 23 to permit the necessary lift of the ball. The outer end of each 40 chain 22 is provided with a ring 24, which may be engaged over an arm or projection 25 when it is desired to lock the ball in an elevated position and prevent automatic coupling.

45 The outer end of the draw-head is horizontally slotted and is provided with a vertical coupling-pin perforation. This construction enables the draw-head to be coupled with any ordinary pin-and-link car-coupling.

50 It will be seen that the car-coupling is simple and comparatively inexpensive in construction, that it is automatic in coupling, and that it is adapted to be readily uncoupled from the tops and sides of cars without going between them. Furthermore, it will be apparent that the operation of uncoupling the cars 55 automatically resets the parts for automatic coupling.

What I claim is—

60 1. In a car-coupling, the combination of a draw-head provided at one side with a concavity and having a housing located above the same, a ball fitting within the housing and adapted to engage the concavities of two draw-heads, a slide mounted on the draw-head and

projecting into the housing and adapted to support the ball in an elevated position, and means for automatically reciprocating the slide when two cars come together for coupling to cause the ball to drop and for reciprocating the slide in the opposite direction when the ball is raised in uncoupling, substantially as described.

2. In a car-coupling, the combination of a draw-head provided at one side with a concavity, a casing arranged over the concavity, a ball fitting within the casing and adapted to engage the concavities of the two draw-heads, a slide mounted on the draw-head, projecting into the casing and supporting the ball in an elevated position, said slide being arranged to be engaged by a draw-head to release the ball, and a lever connected with the slide and arranged to be engaged by the ball when the latter is lifted, whereby the slide is thrown forward or outward, substantially as described.

3. In a car-coupling, the combination of a draw-head provided at one side with a concavity and having a housing located above the same, a ball fitting within the housing and adapted to engage the concavities of two draw-heads, a movable support arranged to receive the ball and hold the same in an elevated position, and a device connecting the ball with the support, whereby when the ball is elevated the support will be carried beneath the same, substantially as described.

4. In a car-coupling, the combination of a draw-head provided with a concavity, a casing, a slide mounted on the draw-head and arranged to project into the casing to form a support, a lever fulcrumed between its ends on the casing, connected at its lower end to the slide and provided at its upper end with an arm extending into the casing and arranged in an inclined position when the slide is withdrawn, and the ball arranged within the casing, adapted to be supported by the slide and capable of engaging the inclined arm of the lever, whereby the slide is thrown forward when the ball is lifted, substantially as described.

5. In a car-coupling, the combination of a draw-head provided at one side with a concavity, a casing mounted over the same, a ball arranged within the casing, a reciprocating slide mounted on the draw-head and adapted to extend across the casing to form a support for the ball, said slide being provided with a laterally-disposed L-shaped arm, a lever fulcrumed on the casing, connected at its lower end to the slide and provided at its upper end with an L-shaped arm extending into the casing, and operating mechanism connected with the ball, substantially as described.

6. In a car-coupling, the combination of a draw-head, a locking device, a chain extending upward from the locking device and designed to be connected with the top of a car and provided between its ends with a pulley

23 mounted on and carried by the said chain, and side chains connected with the said chain at a point below the pulley, passing over the same and extending therefrom in opposite directions to enable the locking device to be operated from the sides of a car, substantially as described.

In testimony that I claim the foregoing as my own I have hereto affixed my signature in the presence of two witnesses.
